UNITED STATES PATENT OFFICE

OSGOOD K. JONES, OF SAN FRANCISCO, CALIFORNIA

CONCRETE FORM

Application filed June 30, 1931. Serial No. 547,889.

This invention relates to concrete forms and especially to a form which is intended for wall structures and the like.

The object of the present invention is to generally improve and simplify the construction or operation of concrete forms of the character described; to provide a form which may be constructed of metal throughout; to provide a form in which all parts may be used over and over again; to provide a spacing element to maintain a predetermined spacing between the side walls of the form; to provide a spacing element which is adjustable to walls of different thickness; to provide a spacing element comprising a central spacing bar, and a pair of removable end members; to provide a spacing element of the character described which forms a guide and a support for a pair of tie wires and an intermediate spacing rod; to provide a spacing element in which the end sections are readily removed after the concrete has partially set, and which leaves cavities in the surface of the wall sufficiently deep to permit the ends of the tie wires to be bent into the cavities and then covered with grouting or a like material so as to leave a smooth finished wall in which the spacing rods and tie wires are thoroughly embedded and covered; to provide a spacing element or unit which may be assembled at any time before placement during erection of the forms so as to reduce time and to simplify the work of assembling and erecting the forms; to provide a form which is strong and substantial in construction and rigidly braced and in which the bracing members are progressively raised as the wall structure increases in height so that the same bracing members may be used over and over until the wall is completed; and further, to provide a form which requires no support but the wall itself and which is so constructed and assembled that while the concrete in the lower portion of the wall is setting, concrete may be poured above the same, and while the last pour is setting the lower part of the form may be stripped, elevated and assembled in position above the last pour; thus permitting setting, pouring,

stripping and assembly operations to continue in proper sequence with comparatively little, if any delay in the work.

The manner in which the form is constructed and assembled is shown by way of illustration in the accompanying drawings, in which:

Fig. 1 is a perspective view of a portion of the form erected in position.

Fig. 2 is a central vertical section of a portion of the form when erected.

Fig. 3 is a sectional view of a portion of a completed wall.

Figs. 4, 5 and 6 illustrate different forms of offset plates.

Fig. 7 is a horizontal section of a portion of the form when erected.

Fig. 8 is a partial side elevation of the exterior portion of the form showing the relative position of the braces and the combination tie and guide plates.

Fig. 9 is a perspective view showing the assembly of the spacing element and the pins, tie and guide plates with which the spacing elements cooperate.

Fig. 10 is a perspective view of the lowermost pins, tie and guide plate.

Referring to the drawings in detail and particularly to Fig. 1, the essential parts of the form are the side plates A forming the side walls of the form; spacing elements B whereby the side walls of the form are tied together and the thickness of the wall determined; bracing bars C whereby strength and rigidity of the form is insured; and a series of combination guide and tie plates C, the function of which will hereinafter be described.

The side plates referred to are in this instance shown as constructed of comparatively thin steel plates or the like, and they may be a foot or more wide, while the length will be such as can be most conveniently handled. A few short lengths will be employed to fill in between window openings, doors and the like, and where column effects are desired on the surface of the wall, offset plates may be employed as indicated in Figs. 4 to 6. While steel plates are preferably employed, wooden

planks or similar material may obviously be used.

The spacing elements indicated at B are best illustrated in Figs. 1 and 9. Each spacing element is similar in construction and the description of one will accordingly suffice. The spacing element comprises a pair of cone shaped members such as indicated at 2 and 3. They may be constructed of pressed steel, 10 cast iron or the like. Their outer ends are open and one or more inturned flanges are provided, as shown at 4. The inner ends have two perforations formed therein, as indicated at 5 and 6, and recesses or sockets 15 7 are also formed at the inner ends to receive and support a spacing rod or bar such as indicated at 8. The perforations 5 and 6 formed at the inner end of each cone are provided so that a pair of tie wires, such as indicated at 9 and 10, may be threaded or passed through the same. The manner in 20 which the spacing elements are assembled and placed in position between the side walls and the form will hereinafter be described. 25 The side walls of the form are, as previously described, formed by the plates A. Means for bracing the side plates when erected is accordingly essential and I beams or T-shaped structural bars, such as indicated at C, are employed.

The combination tie and guide plates are best illustrated in Figs. 1, 7 and 9. They are constructed of thin steel and are substantially square in shape. They are flat and the diagonally opposed corners are cut, as indicated at 11 and 12. The cut portions are then bent upwardly to form a pair of guide lugs 13 and 14. Each plate is also perforated as indicated at 15 and 16 to permit the tie wires to pass through, as will hereinafter be described. The major portion of the combination tie and guide plates employed are of the shape shown in Fig. 9. A few plates are, however, constructed as shown in Figs. 1 and 10. These plates will be known as the bottommost or base plates, as they form a 35 guide and support for the lowermost side plates A and for the bracing bars C. The plates shown in Figs. 1 and 10 are substantially identical in shape to the plates shown in Fig. 9, the only difference being that the lower edge is provided with one small inturned lug 17, while the opposite face is provided with a base flange 18. This is perforated to permit nails or the like to be driven through, as indicated at 19. The plates are 50 otherwise provided with the small lug 20, and this is perforated, as indicated at 21, to receive a tie wire, as will hereinafter be described.

In actual operation, when the form is to be set up it may be accomplished by first placing a pair of timbers on the ground as indicated at 22 in Fig. 1. A plurality of base plates, 65 such as shown in Fig. 10, are then nailed to

the timbers as shown at 19, the spacing between them being determined by the thickness of the wall and the desired spacing between the bracing bars C. When the base plates have been secured, the structural steel 70 bracing members C are placed vertically between the guide lugs 13 and 14 and they are there temporarily held by angle braces or the like not shown, as such bracing merely serves the function of holding the members C in a vertical position until a portion of the mold and wall has been erected.

After the brace plates and the braces C have been placed in position, the lowermost set of plates A are applied to the inner surface of the base plates and are there supported by the inturned lugs 17. A series of spacing units, such as indicated at B, are then placed in position along the upper edge of the lowermost plates A. The spacing units 80 are preferably assembled in the form shown in Fig. 9 before they are placed in position so as to reduce the time required in erecting the molds and also to simplify the operation of erection. Each spacing unit, as assembled in Fig. 9, supports a pair of cones, the tie wires and the combination guide and tie plates D. The plates D are placed between the outer surface of the lowermost plates A and the inner surface of the braces C and the lugs 13 and 14 of the plates are engaged with the flanges of the braces by merely tilting them to an angular position and then reversing the movement so that the lugs may 90 engage the flanges. When the plates are straightened out, the lugs fully engage and the tie wires will rest on the upper edge of the lowermost plates A. The spacing bar or rod 8 is then inserted between the cones and the spacing between the sides plates is thus determined and maintained. The ends of the tie wires passing through one of the plates B are merely bent or knotted as indicated at 24 to prevent them from pulling through. The opposite ends of the tie wires project 100 through the opposite plate D and are comparatively long, so that they may be twisted and tied as the erection and the assembly of the form continues.

When the first series of spacing units has been placed in position, a second set of plates indicated at A' is placed in position and a second set of spacing units indicated at B' is placed on top thereof and the plates D carried thereby are interlocked with the flanges of the bracing members C, as previously described. The free ends of the tie wires are brought downwardly as indicated at 26, while the free ends of the tie wires of the lower spacing units are bent upwardly as indicated at 27. The free ends overlap and they are then grasped by a suitable tool and twisted up tight. The side forms are thus pulled tightly together and a predetermined spacing is maintained between the same by 115 120 125 130

the cones and the spacing rods. The assembly and erection of the form continues until a suitable height is obtained, and if the wall is to be reinforced with steel or the like, this is inserted and secured in the usual manner, either prior to the erection of the form or while the assembly of the form is taking place. The concrete is then poured and after the pour, the operation of erecting and assembling the form is continued. The second section is then poured and while this is setting the bracing bars C are moved upwardly, this being accomplished by means of a screw jack or any other suitable device.

15 The lugs 13 and 14 in the several guide plates merely frictionally secure the brace members C, and as such permits the same to be moved upwardly by a screw jack or the like. When the bracing members have been moved, the tie wires 26 and 27 are cut off close to the plates D. The plates A are then free to be removed and the side form plates A may then be stripped off leaving the bare wall. The parts thus removed may be elevated and assembled at a point above the last pour and the work may thus be continued indefinitely, as the same parts are used over and over again.

After the lower portion of the wall has been stripped, the cone members 2 and 3 are lightly tapped with a hammer or a suitable tool is inserted to engage the inturned lugs 4. By tapping the cones and by exerting an outward pull, the cones are freed and removed. The free ends of the tie wires are then bent into the cavities left by the removed cones, as shown at 30 in Fig. 3, and the cavities may then be filled with a grouting material or the like, thus leaving a smooth finished 40 wall surface in which the spacing bars 8 and the tie wires are thoroughly embedded and covered. When the bracing bars C have been moved upwardly and the lower part of the wall stripped and finished as just described, it is obvious that the wall itself forms a support not only for the side plates A, but also for the bracing bars, the combination tie and guide plates and the spacing units B.

50 Exterior scaffolding, if the wall happens to be an exterior wall, may thus be eliminated and the only scaffolding required will be an interior scaffolding which may be used during the erection of the mold and for the handling of the concrete. The manner of constructing and assembling the form is exceedingly important, as it permits the mold to be quickly erected and properly aligned, and when so erected and aligned it is strong and rigid and it permits portions of the mold to be stripped 55 while other portions containing concrete are setting and while still other portions are being elevated and erected. The work of setting, stripping, assembling, pouring, etc. may thus take place in proper sequence with a comparatively little, if any, loss of time, and

skilled labor may be almost entirely eliminated, as the work to be performed can be taught to practically anyone.

Any thickness of wall may be constructed; for instance, a six inch wall will probably 70 require a spacing rod, such as indicated at 8, approximately three inches in length, and an eight inch wall will require a five inch spacing rod, and so on. The length of the spacing rod determines the thickness of the 75 wall, but the same end sections or cones may be employed whether the wall is of one thickness or another. It should furthermore be understood that when the cones are knocked out of the wall after the concrete is partially 80 set, they will be used over and over again. This is true of all the parts employed, as the only parts remaining in the wall are the spacing rods 8 and tie wires.

It should be noted that the tie wires 9 and 85 10 together with the plates D secure the side forms A against removal in such a manner as to be independent of the bracing bars. This is important, as it permits the bracing bars to be raised or elevated just as soon as the last pour of concrete commences to set and it, furthermore permits the side forms A and plates D to remain in position on the wall as long as desired, or in other words, until such time as they will be required, as they are secured in position entirely independent of the bracing bars.

The manner of tying the wires 9 and 10, that is, in an up and down direction at points between the plates D, is also important as it permits the side forms A to be pulled tightly together in a vertical direction, thus reducing the spacing between the side form plates and preventing leakage of concrete.

100 The forms as constructed and assembled render the same generally adaptable for use in building construction, dam construction, bridge construction, heavy foundations, and in fact, any place where a form is required to hold concrete.

105 While certain features of the present invention are more or less specifically described, I wish it understood that various changes may be resorted to within the scope of the appended claims. Similarly, that the materials and finish of the several parts employed may be such as the manufacture may decide or varying conditions or uses may demand.

110 Having thus described my invention, what I claim and desire to secure by Letters Patent:

115 1. In a form structure of the character described, a plurality of brace bars, a plurality of elongated side plates forming the side walls of the form, a plurality of guide plates interposed between the side plates and the brace bars, and a plurality of spacing units interposed between the side plates.

120 2. In a form structure of the character described, a plurality of brace bars, a plurality 125

130 of elongated side plates forming the side walls of the form, a plurality of guide plates interposed between the side plates and the brace bars, and a plurality of spacing units interposed between the side plates.

- of elongated side plates forming the side walls of the form, a plurality of guide plates interposed between the side plates and the brace bars, a plurality of spacing units interposed between the side plates, and tie wires extending through the spacing units, said wires also extending between the side plates and through the guide plates and tied thereto.
10. In a form structure of the character described, a plurality of brace bars, a plurality of elongated side plates forming the side walls of the form, a plurality of guide plates interposed between the side plates and the brace bars, means frictionally securing the brace bars to the guide plates, a plurality of spacing units interposed between the side plates, and tie wires extending through the spacing units, said wires also extending between the side plates and through the guide plates and tied thereto.
15. In a form structure of the character described, a plurality of brace bars, a plurality of elongated side plates forming the side walls of the form, a plurality of guide plates interposed between the side plates and the brace bars, means frictionally securing the brace bars to the guide plates, a plurality of spacing units interposed between the side plates, and tie wires extending through the spacing units, said wires also extending between the side plates and through the guide plates and tied thereto.
20. In a form structure of the character described, a plurality of brace bars, a plurality of elongated side plates forming the side walls of the form, a plurality of guide plates interposed between the side plates and the brace bars, lugs formed on the guide plates and frictionally securing and guiding the brace bars, and a plurality of cone shaped members disposed between the elongated side plates and engaging the inner faces thereof, spacing bars disposed between the cones and supported thereby, and tie wires extending through the cones, said wires also extending between the side plates and through the guide plates and tied thereto.
25. In a form structure of the character described, a combination tie and guide plate comprising a flat substantially square plate, a pair of guide lugs formed on the plate and said plate being perforated to permit tie wires to pass therethrough.
30. In a form structure of the character described, a combination tie and guide plate comprising a flat substantially square plate, said plate being cut at diagonally opposed corners and the cut portions being bent towards the plate to form a pair of guide lugs, and said plates being perforated to permit tie wires to pass therethrough.
35. In a form structure of the character described, a combination tie, guide and base plate comprising a flat substantially square plate, a perforated base flange on one end of the plate, whereby it may be secured to a support, a pair of guide lugs formed on the plate, and a perforated lug at one side of the plate for the reception of the tie wire.

OSGOOD K. JONES.
